UNITED STATES PATENT OFFICE

2,500,362

STOCK CAR PARTITION

Edward W. Kidwell, Ogden Dunes, Ind.

Application June 8, 1945, Serial No. 598,231

4 Claims. (Cl. 160—216)

1

It is frequently necessary to put a partition across a stock car, as for example when cattle are to be placed in one end of the car and sheep in the other end. There have been various suggestions for built-in or prefabricated partitions but none of them have really satisfied the need and hence the common practice has been to have carpenters build the partition in the car when required.

One reason why previous suggestions have been unsatisfactory is because stock cars are not uniform in width. Accordingly if a partition is to be interchangeable between cars it must be adjustable. Proposals for adjustable partitions heretofore have not been sufficiently simple. Simplicity is desirable both in construction, to minimize cost, and in operation to facilitate application to the car.

According to the present invention the partition may be made entirely of lumber and spikes and it is formed of two rigid parts which telescope with respect to one another sufficiently to fit different stock cars.

Additional objects and advantages of the invention will be apparent from the description and from the drawings in which

Fig. 1 is a fragmentary transverse sectional view through a stock car showing the side elevation of the partition chosen for illustration of this invention;

Fig. 2 is a fragmentary horizontal sectional view showing the top view of the partition;

Fig. 3 is a view corresponding to Fig. 1 but showing the partition collapsed and being inserted;

Fig. 4 is a fragmentary sectional detailed view taken approximately on the line 4—4 of Fig. 3;

Fig. 5 is a fragmentary sectional view taken approximately on the line 5—5 of Fig. 1.

Although the law requires a full and exact description of at least one form of the invention, such as that which follows, it is, of course, the purpose of a patent to cover each new inventive concept therein no matter how it may later be disguised by variations in form or additions of further improvements; and the appended claims are intended to accomplish this purpose by particularly pointing out the parts, improvements, or combinations in which the inventive concepts are found.

In the illustrated form of the invention the partition includes end posts 11 and 12, intermediate posts 13 and 14, top rail 16, intermediate rail 17, and bottom rail 18.

As seen in Fig. 2 each of the posts includes

2

two upright boards. These boards are secured together and to appropriate rails by spikes 19.

As indicated by the spike positions in Figures 1 and 3, the two boards of post 11 are rigidly spiked to intermediate rail 17. Likewise the two boards of post 14 are rigidly spiked to rail 17. On the other hand the two boards of post 13 and the two boards of the post 12 are all spiked rigidly to upper and lower rails 16 and 18.

From the foregoing it is seen that upper and lower rails 16 and 18 together with posts 12 and 13 make up one rigid unit. Intermediate rail 17 and posts 11 and 14 make up another rigid unit. These two units are not secured together and hence may telescope with respect to one another. Thus it will be seen that rails 16 and 18 slide between the two boards of post 11 and also between the two boards of post 14. Intermediate rail 17 slides between the two boards of post 13 and the two boards of post 12. To guide the rails in their sliding movement, and also to add some rigidity to the post construction, spikes 21 are provided below each rail where it slides through a post and also above each of rails 17 and 18 where either one slides through a post.

The structure as thus described is firm enough to be carried around and carried into a car easily.

The length of the rails 16, 17, and 18, could be the inside width of the narrowest cars in which the partition is likely to be used. At the present time the length preferred is 8 ft. 3 inches. This then will be the length of the partition when it is fully collapsed as seen in Fig. 3. It can then be expanded almost the full width of the post 11 without being materially weakened since all of the rails will still extend into all of the posts.

A collapsed length of an even eight feet may be preferred by some shippers, because some cars are that narrow. Occasionally there are exceptionally wide cars which may require expanding such a partition until the rails 16 and 18 have been drawn entirely out of post 11 and the rails 17 entirely out of post 12. It has been found that this is not objectionable since the partition has adequate strength.

If it should be desired to make the partition of somewhat lighter lumber, it might not have adequate strength when expanded to draw the rails out of the end posts. Accordingly if such light lumber is used it will be desirable either to make the rails a little longer and for extremely narrow cars cut them off or leave the partition at a slight angle, or else to use wider boards for the posts 11 and 12. Alternatively additional

posts similar to posts 13 and 14 could be provided close to the posts 11 and 12.

The drawings are approximately to scale. The rails 16, 17, and 18 are preferably nominally 2" x 6" planks. The posts 11 and 12 are preferably formed of planks which are nominally 2" x 8".

The space between rails 17 and 18 is large enough so that some small animals can climb between these rails. Accordingly if such animals are being shipped it is desirable to insert an additional bar 23 through the posts 13 and 14 and extending into posts 11 and 12. Spikes 24 are preferably provided in all partitions for the bar 23 to rest on, if it should be required.

The partition may be secured in place in any desired manner. For example, bolts 26 may be provided, equipped with cleats 27 and 28. The cleats 27 will be turned in a generally vertical position to straddle two of the boards 29 forming a side wall of the car. The cleat 28 will be turned in a generally horizontal position to straddle two boards of one of the posts 11 or 12. A nut, such as wing nut 31 can be tightened on bolt 26 to clamp post 11 firmly against boards 29.

It will often be preferred merely to use lengths of wires 32 instead of bolts 26, especially if the bolt would interfere with the bar 23. The wire may be applied as seen at the lower portion of Fig. 1 by being passed around one of the boards 29 and around one or both of the boards of the post 11, the two ends of the wire being twisted together. The car uprights 33 or diagonal bracing members are usually close enough together so there is no danger of the wire 32 sliding too far along a bar 29. Of course it can easily be twisted tightly enough so that it will ordinarily not slide at all.

From the foregoing it is seen that a partition has been invented which can be manufactured very simply and inexpensively from ordinary lumber and which may easily be applied to stock cars of varying widths. All of the lumber comprises simple boards having no expensive, special shaping. Anyone who ships stock frequently can maintain a supply of these partitions and one of them can be adjusted in place by the stock handlers whenever required. Heretofore it has often been deemed necessary to have a crew of carpenters at hand when such a partition was to be required. There have even been times in which the carpenters have had to wait idly for hours due to delay in receipt of the car in which they were to build a partition. Built-in partitions in the cars were usually scrapped when removed and the removal required a substantial amount of work. The present partitions can often be reused because they can be removed easily and without damage.

I claim:

1. A partition for stock cars including two end posts and two intermediate posts all in alignment, each comprising two vertically extending boards; at least three vertically spaced rails of substantially equal length two of which are secured to one end post and one to the other end

post, each of which rails extends from the post to which it is secured slideably between the boards of an intermediate post, and thence between the boards of the other intermediate post, being secured thereto, and extends therebeyond to extend between the boards of the other end post while all of said posts are spaced substantially apart.

2. A partition for stock cars including two end posts and two intermediate posts all in alignment; at least three vertically spaced rails of substantially equal length two of which are secured to one end post and one to the other end post, each of which rails extends from the end post to which it is secured past an intermediate post in guided sliding relationship therewith and thence to the other intermediate post, to which it is secured, and extending therebeyond to extend into guided sliding relationship with the other end post while all of said posts are substantially spaced apart.

3. A partition for stock cars including two end posts and at least one intermediate post all substantially in alignment; and at least three vertically spaced rails forming with the posts two telescoping units, one unit having upper and lower generally horizontal rails secured at one end to one of the end posts and at an intermediate point to an intermediate post, and the other unit including a generally horizontal rail spaced vertically from the other rails and secured at one end to the other end post, and each rail having a guided sliding relationship with each post of the other unit while the posts are all spaced substantially apart.

4. A partition for stock cars including two end posts and at least one intermediate post all substantially in alignment; and at least three vertically spaced rails forming with the post two telescoping units, one unit having upper and lower generally horizontal rails secured at one end to one of the end posts and at an intermediate point to an intermediate post, and the other unit including a generally horizontal rail spaced vertically from the other rails and secured at one end to the other end post, each of said posts including two boards, one on each side of the rails, and each of said rails being guided within each post of the other unit, while the posts are all spaced substantially apart, by means extending between and into the boards of the posts, at least one of the rails being thus guided both above and below said rail to provide a firm construction.

EDWARD W. KIDWELL.
